WILLIAM WADE SMITH, OF DARLINGTON, MARYLAND, ASSIGNOR OF ONE-HALF TO
STANLEY S. SPENCER, OF DARLINGTON, MARYLAND.

NON-REFILLABLE BOTTLE.

1,098,988.

Specification of Letters Patent.

Patented June 2, 1914.

Application filed December 11, 1913. Serial No. 805,995.

To all whom it may concern:

Be it known that I, WILLIAM W. SMITH, a citizen of the United States, and a resident of Darlington, in the county of Harford and 5 State of Maryland, have made certain new and useful Improvements in Non-Refillable Bottles, of which the following is a specification.

My invention relates to improvements in 10 non-refillable bottles, and it consists in the combinations, constructions, and arrangements herein described and claimed.

An object of my invention is to provide a 15 receptacle for holding liquids from which the liquids may be readily poured, but into which the liquids cannot be readily returned after it is once emptied.

A further object of my invention is to 20 provide a device of the type described which is of a relatively simple nature and therefore is cheap to manufacture.

Other objects and advantages will appear 25 in the following specification and the novel features of the device will be particularly pointed out in the appended claim.

My invention is illustrated in the accompanying drawings forming part of this application in which—

Figure 1 is a section through the neck of 30 the bottle or receptacle showing the latter in its normally closed condition, and Fig. 2 is a similar section showing the bottle tipped to permit the emptying of the contents thereof. Fig. 3 is a plan view of the bottle 35 closure.

In carrying out my invention I make use 40 of a receptacle of any suitable shape or material. In the present instance I have shown the receptacle as consisting of a bottle having a body portion 1 at the top of which is a neck formed like that shown in Fig. 1. It will be seen that the neck is constricted at a point 2 just above where it joins the body portion. From this point it tapers outwardly to a point 3. The portion between the point 3 and the point 4 is substantially cylindrical. A shoulder 5 is disposed on the inner side of the neck at this point, while above the shoulder 5 is a shoulder 6. The 45 latter is formed by curving the sides of the bottle so as to form a bead 6^x on the outside thereof which adds to the appearance of the bottle, and at the same time makes it stronger. From the shoulder 6 to the bead 50 6^x the neck is fashioned on a double curve

as clearly shown in Fig. 1, while between the point 7 and the top of the bottle 8 the inner portion of the neck is tapered so as to hold the cork 9 securely.

The closure for the bottle consists preferably of an impervious body portion 10 which is preferably of porcelain, and which is tapered in the manner shown in Fig. 1. It is held in a metal ring 11 which has a series of outwardly bent spring fingers 12 made 60 integral with the ring, and a series of inwardly bent spring fingers 13 also integral with the ring and shorter than the fingers 12.

From the foregoing description of the various parts of the device the operation 70 thereof may be readily understood.

The closure 10 is designed to fit tightly within the ring 11, but in order to prevent it from slipping out therefrom the spring fingers 13 are bent inwardly, as shown. The 75 bottle or receptacle is filled in the ordinary manner and when filled the closure is thrust through the upper end and forced downwardly by means of a stick or other convenient tool, the spring fingers 12 bending 80 inwardly until the lower portion of the neck is reached when the closure 10 will enter the constricted portion 2, thereby effectually stopping up the latter. The bottom portion of the neck is wide enough so that the spring 85 fingers 12 exert little or no tension on the sides of the neck.

Now when it is desired to pour out the contents of the bottle it is tipped in the manner shown in Fig. 3, when the closure 90 10 will fall away from the opening at 2, thus permitting the liquid to pass by the closure and by the spring fingers and out through the mouth of the bottle. It will be observed that the shoulders 5 prevent the 95 passage of the closure out of the bottle. If during the movement of the closure the spring fingers 12 on one side should happen to pass the shoulder 5 they will be stopped by the shoulder 6, which, it will be observed, 100 extends farther in toward the center of the neck. Any attempt to force liquid into the bottle will result in forcing the closure into the constricted portion 2, thereby effectually sealing the bottle. Under certain conditions small portions of liquid may be forced past the closure, but not enough of the liquid can be forced past in order to make commercial use of the bottle for purposes of 105 again dispensing liquid therefrom. The de- 110

vice may be cheaply manufactured in quantity for the reason that it is simple in construction.

I claim:—

- 5 In a non-refillable bottle, a body portion, a neck therefor, said neck having a cylindrical portion tapering to a constricted portion near its union with the body portion and having a reduced portion at its top, a shoulder disposed between said cylindrical portion and said reduced portion, a closure for said constricted portion, said closure comprising an impervious tapered body portion, a metal ring surrounding one end of said
- 10

body portion, and integral spring fingers 15 carried by said metal ring, certain of said spring fingers being bent inwardly toward one another and other of said spring fingers being bent outwardly, said outwardly bent spring fingers being arranged to engage 20 said shoulder for preventing the dislodgment of the closure from the neck of the bottle.

WILLIAM WADE SMITH.
